CLAIM

The ornamental design for an automotive hood ornament, as shown.

DESCRIPTION

FIG. 1 is a top plan view of an automotive hood ornament showing my new design;

FIG. 2 is a side elevational view thereof, the opposite side being a mirror image of the side shown herein;

FIG. 3 is a bottom plan view thereof;

FIG. 4 is a front elevational view thereof; and

FIG. 5 is a rear elevational view thereof.
